CARBURETOR

Filed May 26, 1924

UNITED STATES PATENT OFFICE

CHARLES LAWRENCE STOKES, OF LOS ANGELES, CALIFORNIA, ASSIGNOR TO CURTIS B. CAMP, TRUSTEE, OF GLENCOE, ILLINOIS

CARBURETOR

Application filed May 26, 1924. Serial No. 715,912.

My invention relates to improvements in automatic fuel regulators for carburetors, in which the carburetor may be automatically primed and thereafter the fuel supply there- 5 to may be automatically governed.

The principal object of my invention is to provide an automatic fuel regulator for a carburetor which will so control the rate of liquid fuel fed through the carburetor 10 to an internal combustion engine that the mixture of fuel and air supplied to the engine will normally be a mixture providing maximum economy for light loads and thereafter when heavy loads are put on the engine the 15 fuel will be automatically increased for maximum power.

A further object of my invention is to provide automatic priming and accelerating means for an engine in conjunction with my 20 carburetor.

A further object of my invention is to control the automatic fuel regulation, priming, and accelerating means of my carburetor by the engine induction vacuum.

25 There are many makes of carburetors known at the present time in active use in which great study has been given to obtain the effect now shown in my carburetor. Owing to inherent defects in the design the 30 fuel mixtures provided for said makes of carburetors are invariably too rich for the reason that if said carburetors are set to give a lean mixture throughout a range of engine speeds, the mixture will then be too lean 35 for maximum power. Therefore, in order to get the best average results from said carburetors, the same are adjusted to give a rich mixture throughout the range of service demanded of them.

40 By my invention, I am now enabled to provide an engine with a lean mixture for light loads, and thereafter as the load is increased, I am enabled to automatically increase the richness of the mixture so that 45 the engine will develop maximum power. In other words, if the throttle on my carburetor be set at any given position and the load on the engine be increased or decreased at that 50 throttle opening, the engine will run with maximum economy at light loads and with

maximum power as the load reaches its peak.

This I am now enabled to do in a simple manner by apparatus illustrated in the drawings, in which the same numbers indicate like parts and wherein:

55

Fig. 1 is a view of the general arrangements of my carburetor attached to an internal combustion engine.

Fig. 2 is a vertical section showing the particular arrangements of the parts of my 60 carburetor.

Fig. 3 is a vertical sectional view along the lines 3—3 of Fig. 2.

Fig. 4 is a view of part of Fig. 2.

Fig. 5 is a sectional detail of a novel thermostat shown in Fig. 1.

Fig. 6 is a sectional view along the lines 6—6 of Fig. 2.

An internal combustion engine 1 has the usual exhaust pipe 2 and inlet manifold 3. 70 A carburetor 4 is attached to the intake manifold 3, said carburetor being supplied in any well known manner with liquid fuel through a pipe 5. The carburetor 4 is provided with the usual throttle valve 6 for controlling the supply of liquid fuel and air to 1 and with a choker valve 7 for priming the engine 1 for starting.

The carburetor 4 is largely of a conventional design, being constructed with a float chamber 8 containing an annular float 9 which operates the usual needle valve 10 for cutting off, or admitting, fuel from 5 and the liquid level in 8 normally stands at the level A—A.

80 A compensating well 11 receives its liquid fuel from 8 through a calibrated orifice 12 and supplies said fuel to a nozzle 13 responsive to the induction vacuum of 1. The upper part of 11 is closed and a pipe 13a is led therefrom to a fitting 14 comprising a cover for an accelerating chamber 15 and said chamber contains a flexible diaphragm valve, or bellows, 16 well known to the trade as a "sylphon". The upper part of 16 is closed 85 by a cap 17 which supports a valve 18 for opening and closing one end of 13a. The upper part of 14 terminates in a sleeve for guiding 18, which sleeve contains a plurality 90 of air ports 19 for admitting atmosphere to 95 100

13a and 11 when the valve 18 is unseated. The lower part of 16 is closed by a cap 20 adapted to seal the chamber 15 air tight and in 20 is placed a fitting 21 containing a downwardly seating check valve 22 and, normally, check valve 22 is seated tight in 21 with the exception of a very minute leak 23 provided in the seat for 22, the purpose of which will be later described. A pipe 24 is securely coupled to 21 by a compression nut 25 for applying vacuum to the interior of 16, said vacuum being taken from the manifold 3 on the engine side of throttle 6.

10 The chamber 15 receives liquid fuel from 8 through a very minute leak 25 and the air spaces between 8 and 15 are connected through a relatively large port 26.

15 A cover 27 encloses the top of 8 and renders the same normally air tight except under such conditions as will be later described wherein a predetermined amount of air constantly leaks into 8 through a very minute hole 28 placed in a bend in a fitting 29 adapted to hold an inwardly opening check valve 30, 29 being securely fastened to the outside of 27.

20 The choker valve 7 may be manually controlled but in addition thereto I prefer to provide automatic choking and accelerating means which comprise a sylphon 31 held in a 30 casing 32, the upper parts of 31 and 32 being closed by a cap 33 which terminates in a sleeve 34 containing a downwardly seating check valve 35 the seat therefor containing a minute hole 36. The lower part of 31 is closed by 35 a disc 37 to which is attached a forked stem 38 adapted to fit over a ratchet 39 fastened to the spindle 40 for operating the choker valve 7 by means of a pin 41. The ratchet comprises a long tooth 42 and a short tooth 43 and the same is firmly fastened on the spindle 40, the other end of 40 containing a fitting 44 to which is attached a spring (not shown) whereby the choker valve 7 is normally held open as shown in Fig. 2. Any 45 tendency to move 7 from a horizontal position is normally resisted by the action of said spring.

25 A pipe 45 is fastened to 34 for applying the engine vacuum to the interior of 31 by means of a pipe 46 one end of which is fastened to the manifold 3 on the engine side of throttle 6. The other end of 46 leads to a thermostat placed in the exhaust 2, which thermostat comprises a barrel 47 closed at the upper end 55 by a nut 48 and at the lower end by a nut 49 into which latter 46 is fastened. Centrally of 47 on 49 is a boss 50 adapted to be closed by a valve head 51 the stem of which comprises a tube 52 extending through the center of 48 and being held thereon by a nut 53, the upper end of 52 being open to atmosphere. Centrally of 51 a minute hole 54 is drilled which provides communication from the interior of 52 to the interior of 46 and thence 60 through a small hole 55 to the interior of 3.

A series of small holes 56 are drilled in 52 for a purpose to be later described.

65 The operation of my carburetor for obtaining a desired ratio of liquid fuel to air which will give maximum economy and maximum power when desired is as follows:

70 By referring to Fig. 2 it will be assumed that engine 1 is normally running with the throttle 6 substantially closed, the engine 1 will be on very light load and therefore the 75 vacuum in 3 will be very high, let it be assumed to be 20 inches of mercury vacuum. This degree of vacuum actually is applied through the pipe 24 and hole 23 to the interior of 16, whereupon 16 will contract, very 80 slowly on account of the minute hole 23, thereby unseating the valve 18 and permitting free access of air through 19 and 13a to 11.

85 In this manner it will be clearly understood that the amount of fuel supplied through 13 will be solely that which will flow through the orifice 12 into the chamber 11, the rate of feed to 12 and 13 under a high vacuum as described being very small because the vacuum on 13, below the throttle 6, will probably not amount to more than one-half inch of gasoline suction.

90 While this condition exists, it will be understood that 8 is open to atmosphere through the minute hole 28 and in 95 fact 8 is always under atmospheric, or super-atmospheric, pressure owing to the action of check valve 30 which, should the action of 16 in contracting cause any degree of vacuum in 8, will open and immediately restore atmospheric pressure to 8.

100 If now it be assumed that throttle 6 be one-quarter open, the degree of suction applied through 24 will drop to say ten inches of mercury. At the same time the suction on 105 13 will have increased say to three inches of gasoline. The reduction of vacuum in 24 due to the part opening of 6 causes an expansion of 16 to the end that the entry of atmosphere through 19 to the pipe 13a is reduced thereby rendering more effective the application of the increased suction to 13 and thereby to 110 12.

115 This result thereby increases the flow of fuel through 12 for the purpose of providing a maximum economy mixture at that throttle opening and the tapered end of valve 18 is arranged to the end, that the opening and closing of 18 shall admit air through 19 to govern the suction applied through 13 to 12 for giving the desired result this is, as before stated, maximum economy at light loads and maximum power when required, therefore it is to be understood that I do not limit myself to a straight taper as illustrated but the tapered end of 18 may be turned and consist of a varying number of different tapers, or shoulders, fashioned in any desired manner to control the suction on 12 for the purpose described.

120 125 130 It is well known that a compensating

well 11 open to atmosphere and supplied with fuel through a nozzle 12 under constant heat will cause the mixture supplied to an engine to get leaner as the engine suction on the nozzle 13 increases.

5 This is shown and illustrated in the well-known Zenith carburetor, which normally provides two nozzles, one of which increases its rate of fuel delivery as the engine suction thereon increases. In this manner said Zenith carburetor attains a compensating effect by the use of two nozzles but without obtaining the mixture proportions which I am now enabled to provide through one nozzle. At 10 the same time it is to be understood that I do not limit myself to the use of one nozzle, inasmuch as I am enabled to effect like results with any carburetor comprising a compensating well.

20 If now it be assumed that throttle 6 is substantially closed at idling speeds, and the same be forced wide open for sudden acceleration, the well 11 being normally full to the level A—A during idling conditions, 25 the vacuum in 3 will drop substantially to zero whereupon 16 will expand its full length quickly, due to the sudden opening of 22, and will cut off the supply of air through 19 to 11. There will be allowed however a sufficient air leak around the seat of 18 to provide that the sudden increase of suction on 30 13, due to the sudden opening of 6, will cause well 11 to be quickly emptied and thereafter the compression of air in the upper part of 35 15, will cause a like compression in the upper part of 8 for forcing an augmented supply of liquid fuel through 12 to prolong the acceleration until the super-atmospheric pressure in 8 and 15 will have been reduced to 40 atmospheric pressure. It will be understood that during this compression a slight leak of air will occur outwardly through 28, but 28 is of such small size that the loss of air there-through is not sufficient to substantially 45 affect my desired result.

In this manner it will be seen that my device is very useful for providing an accelerating charge to an engine, the same being a function of its fuel regulating functions 50 and the same is very easily applicable, not alone to the carburetor herein illustrated but also to many other well-known makes of carburetors now on the market.

It will be especially noted that the supply 55 of fuel in 15, which is maintained through the minute hole 25, remains substantially constant, because the chamber 15 is so designed with respect to the liquid level A—A and the passage 26 that the rise of liquid fuel 60 in 15, due to the sudden expansion of 16, will not permit liquid fuel to be forced through 26, there being but a very slight flow of liquid fuel back and forth through the hole 25, but such flow has not an appreciable effect on 65 the liquid level in 8. Of course, it is readily

apparent that a check valve inwardly opening to 15 might also be used in place of 25, but the size of 25 is such that it is, in effect, a check valve itself.

It is also possible, when starting the engine 1 to obtain a priming mixture by rapidly opening and closing 6 when the engine 1 is being cranked, because in this manner excess fuel will be forced through 12 for ultimately raising the level and overflowing 75 from 13, but such priming is better accomplished as shown and described in my co-pending applications S. N. 626,990, filed March 22, 1923, which matured into Patent 1,694,801 issued Dec. 11, 1928, S. N. 644,923 filed June 12, 1923, which matured into Patent 1,750,766 issued March 18, 1930, S. N. 676,864 filed November 24, 1923, and in another application executed of even date hereof. In my co-pending application S. N. 676,864 80 filed November 24, 1923, I provide means for automatically closing the choker valve 7 at starting periods and I am now enabled to adapt the principle therein outlined to good effect for choking and accelerating according to the engine vacuum. In this apparatus as shown in detail in Figs. 3 and 4, I make particular use of the fact that the engine vacuum in 3 is low at cranking speeds and very much higher at idling speeds when 90 the engine has fired.

To utilize this knowledge, I provide that the spindle 40 shall extend a certain distance so that 38 and 41 shall surround the ratchet 39 and 41 shall, particularly, just about 100 touch the short tooth 43 when the engine is dead. If it be assumed that the engine 1 and exhaust pipe 2 are cold, the valve 51 will be tightly seated on 40 because I provide that 51 and 52 shall be made of a metal having a different coefficient of expansion to 47 for instance 51 and 52 may be made of the nickel iron alloy known as "invar", while 47 is made of brass. Therefore upon cranking the engine 1 a vacuum of about 8 inches of 110 mercury will be induced in 3 and applied through 55, 46, and 36 to the interior of 31. This vacuum will be slightly reduced by the stream of air flowing through 52 and 54 but not appreciably because of the minute hole 115 54. This vacuum causes 31 to contract rapidly because 35 will lift from its seat, atmospheric pressure being supplied to the exterior of 31 through a passage 57 joining the interior of 32 with the air inlet of carburetor 4 on the atmosphere side of choker 7.

The contraction of 31 causes the pin 41 to actuate the short tooth 43 to the end that the choker valve 7 substantially closes the air passage 58, whereupon, 18 being unseated, the high vacuum in 3 is exerted on 13 for supplying an excess of fuel to the engine 1. This excess of fuel is sufficient to cause the engine to fire, whereupon the vacuum in 3 is immediately increased and applied to 120 125 130

the interior of 31 causing a further contraction thereof. This further contraction of 31 causes the pin 41 to slip past the small tooth 43, whereupon the spring attached to 44 will cause the long tooth 42 to be engaged with the pin 41, thus causing 7 to open a predetermined distance sufficient to relieve the vacuum on 13 for drawing further fuel there-through when 7 is in said predetermined position.

Thereafter, upon further opening of the throttle 6, the vacuum applied to the interior of 31 will be proportionately and slowly reduced because the check valve 35 will be tightly seated and the inflow of air to 31 will be checked by the minute opening 36. Therefore upon the sudden opening of 6, there will be a lag in the opening of 7 and this lag is utilized to induce a higher suction on the nozzle 13 for increasing the accelerating charge to be drawn through 12, it being noted that 16 will expand suddenly due to the position of check valve 22.

At the same time, after providing a priming charge, it will be noted that the position of 7 will normally be wide open when 6 is wide open because, not only will there be substantially the same vacuum on the inside and outside of 31, due to the passage 57, but also because the spring-like action of 31 tends to normally expand the same to its full length. It should be noted however, that while, under such conditions, the vacuum on the inside and outside of 31 is substantially the same, there exists a slight difference between the vacuum in 58 and 3 sufficient to prevent the return of 41 to its normal position for starting to the end that as long as the engine is running a priming charge will not be induced by the closing of 7 when 6 is suddenly closed.

It will thus be seen that the valve 7 responds to and follows the movement of 6, except that when the engine is first started, the valve 7 will be fully closed for inducing a priming charge to 13.

This movement is an improvement on my aforementioned application S. N. 676,864, filed November 24, 1923, and in connection therewith I now provide a thermostatic regulator adapted to reduce the movement of 7 according to the engine temperature. If it be assumed that 1 and 2 are cold, the first priming charge induced by the closing of 7 as described will cause the heat of the exhaust to be applied to 47 which, being made of brass expands rather rapidly because not only are 51 and 52 made of a metal having a low co-efficient of expansion, but they are further aided in not expanding due to the cooling effect of the stream of air passing through 52 and 54 responsive to the vacuum applied through 46.

The expansion of 47 therefore causes an annular space between 51 and 50 whereupon

further air will be diverted through 56 and around 51 into 50. This flow of air causes a reduction in the vacuum applied to the interior of 31 thereby reducing the movement of 31 and governing the same according to the temperature of the gases passing through 2. The effect of this is to cause 7 to perform its priming function and thereafter to be safely regulated for the purpose of not causing too rich a mixture to be induced through 13 when the engine 1 attains a running temperature.

A similar effect may be obtained, although in different degree, by eliminating 47, plugging the end of pipe 46 connected thereto, and substituting a flat strip of by-metallic construction for the stem 38. Such strip would then be adapted to move the pin 41 to and from the center of 39 along the face of 43 to the end that at lower and higher atmospheric and engine temperatures, the pin 41 would cause a greater or less movement of 39 for closing 7.

In other words, such a thermostatic strip would govern the choking effect of 7 according to both atmospheric and engine temperatures.

It should be here understood that the priming and accelerating means co-ordinated in the sylphon 31, the choker 7, and thermostat 47 may be used in conjunction with the accelerating and priming means comprising the well 7 and sylphon 16, or the same may be used separately as desired, the provision being made herein to provide a carburetor having several adaptable devices which may be co-ordinated to give the best results.

In Fig. 6 is illustrated a priming and idling means for the carburetor 4 wherein a chamber 59 is fed with liquid fuel from the accelerating well 11 and 59 is normally full to the level A—A.

When the throttle 6 is closed, as it usually is at starting position, the engine vacuum in 3 is applied through a pipe 60, which pipe extends substantially to the bottom of 59 below the fuel level A—A and ends a slight distance above a nozzle 61 containing a small orifice 62 adapted to be of such a size as to provide sufficient fuel for causing the engine 1 to idle.

The upper end of 59 is closed air-tight and the admission of atmosphere thereto is governed by a valve 63 through a passage 64.

In this manner it will be seen that when the engine 1 is cranked, the high vacuum in 3 will cause the liquid fuel in 59 to be rapidly withdrawn thereby assisting the engine to start and this withdrawal of fuel from 59, due to the atmospheric pressure through 63, will uncover the lower end of 60 and thereafter sufficient fuel will be induced by said vacuum through 62 for forming, in conjunction with the air admitted through 63, the

proper mixture for causing the engine 1 to idle and this mixture can be varied according to the adjustment provided in 63.

As soon as the throttle 6 is further opened 5 and the accelerating well 11 is empty, it will be noted that no fuel will be supplied through 62 due to the diversion of the same through 13, but when the engine 1 is dead, liquid fuel will again fill 11 and 59 through 25, 65, and 62 to the level A—A.

10 The carburetor 4, as a unit, may be used without the auxiliary priming and accelerating means contained in 32 and it is obvious that all the priming and accelerating means 15 described may be used conjointly, or individually, according to any particular design. It is also obvious that if it is not desired to use 16 for accelerating by placing air pressure on 8, a simple vacuum and spring controlled pis- 20 ton may be substituted for operating the valve 18, in which case the ports 25 and 26 will be closed air tight.

Other forms of thermostatic control may be used to govern the use of 31 and the same 25 may be placed in the water circulating system of engine 1 or, if 58 is connected to 2 by a hot air pipe, such thermostatic control may be placed therein.

I claim:

30 1. In an internal combustion engine, an intake passage, a throttle in said passage, a carburetor for supplying an explosive mixture to said engine through said passage, said carburetor comprising a fuel chamber, a compensating well and a nozzle in communication with said chamber, and means for automatically progressively reducing the pressure in said well, by proportionately reducing the amount of air supplied thereto as said 40 throttle is opened at low speeds only.

2. In a carburetor, a carburetor chamber for mixing air and fuel by suction, a throttle in the chamber, a nozzle for supplying fuel to the chamber, a fuel chamber for supplying fuel to said nozzle, said last named chamber being provided with a fuel inlet, a float controlled valve for said inlet, means governed by said suction for controlling the flow of fuel through the nozzle, said means comprising mechanism for temporarily increasing the pressure in said fuel chamber during the sudden acceleration of the engine, and means for automatically controlling the supply of air to said nozzle.

55 3. In a carburetor, a mixing chamber for mixing air and fuel by suction, a throttle in the chamber, a nozzle for supplying fuel to the mixing chamber, a fuel reservoir for supplying fuel to the nozzle, a fuel inlet for said fuel reservoir, a float controlled valve for said inlet, a chamber and expansible means therein governed by suction for controlling the flow of fuel through the nozzle, said expansible means in said chamber effecting pressure therein to effect a temporary increase of

pressure in said fuel reservoir during the sudden acceleration of the engine and means for automatically controlling the supply of air through said nozzle.

4. In a carburetor, a mixing chamber for 70 mixing air and fuel by suction, a throttle in the chamber, a nozzle for supplying fuel to the mixing chamber, a fuel reservoir for supplying fuel to the nozzle, a fuel inlet for said fuel reservoir and a float controlled valve 75 for said inlet, a chamber and expansible means therein governed by suction for controlling the flow of fuel through the nozzle, a port connecting said reservoir and said chamber, said expansible means effecting 80 pressure in said chamber to effect a temporary increase of pressure in said fuel reservoir during the sudden acceleration of the engine and means for automatically controlling the supply of air to said nozzle. 85

5. In a carburetor, a mixing chamber for 90 mixing air and fuel by suction, a throttle in the chamber, a nozzle for supplying fuel to the mixing chamber, a fuel reservoir for supplying fuel to the nozzle, a fuel inlet for said fuel reservoir and a float controlled valve for said inlet, a chamber and expansible means therein governed by suction for controlling the flow of fuel through the nozzle, an outlet port in said mixing chamber above said throttle and a connection between said port and said expansible means, said means effective to create a temporary increase in pressure in said fuel reservoir during a sudden acceleration of the engine, and means for automatically controlling the supply of air through said nozzle. 95

6. In a carburetor, a mixing chamber for 100 mixing air and fuel by suction, a throttle in the chamber, a nozzle for supplying fuel to the mixing chamber, a fuel reservoir for supplying fuel to the nozzle, a chamber and expansible means therein governed by suction for controlling the flow of fuel through the nozzle, a port connecting said reservoir and said chamber above the fuel level in the same, said expansible means effective to create a temporary increase in atmospheric pressure in said fuel reservoir during a sudden acceleration of the engine to increase the flow of fuel through said nozzle and means controlled by said expansible means for automatically controlling the supply of air to said nozzle. 110

7. In a carburetor, a mixing chamber for 115 mixing air and fuel by suction, a throttle in said chamber controlling said suction, a nozzle for supplying fuel to the mixing chamber, a fuel reservoir for supplying fuel to the nozzle, expansible means effected by varying degrees of suction for controlling the quantity of fuel flowing through said nozzle and means controlled by the varying degrees of expansion or contraction of said expansible 120

means for controlling the supply of air to said nozzle.

8. In a carburetor, a mixing chamber for mixing air and fuel by suction, a throttle in said chamber, a nozzle for supplying fuel to the mixing chamber, a fuel reservoir for supplying fuel to the nozzle, expansible means effected by varying degrees of suction for controlling the quantity of fuel flowing through the nozzle and means simultaneously controlled by the varying degrees of expansion or contraction of said expansible means for controlling the supply of air through said nozzle.
- 15 9. In a carburetor, a mixing chamber for mixing air and fuel by suction, a throttle in said chamber, a nozzle for supplying fuel to the mixing chamber, a fuel reservoir for supplying fuel to the nozzle, a chamber and expansible means therein, a port in said mixing chamber above said throttle and a connection between said port and said expansible means, said means effected by varying degrees of suction at the port for controlling the quantity of fuel flowing through said port, said expansible means effecting the temporary increase of pressure in the fuel reservoir during a sudden acceleration of the engine and means simultaneously controlled by the varying degrees of expansion or contraction of said expansible means for controlling the supply of air to said nozzle.

Signed at Wilmington, in the county of Los Angeles and State of California, this

35 21st day of March, A. D. 1924.
